FOREIGN PATENT DOCUMENTS

GB 4007138 * 7/2008

Primary Examiner — Catherine Tuttle(74) *Attorney, Agent, or Firm* — Aka Chan LLP(57) **CLAIM**

The ornamental design for a soccer box, as shown and described.

DESCRIPTION

FIG. 1 shows a perspective view of a first embodiment of a design for a soccer box, from above the soccer box.

FIG. 2 shows a side view of FIG. 1.

FIG. 3 shows a top view of FIG. 1.

FIG. 4 shows a bottom view of FIG. 1.

FIG. 5 shows a perspective view of FIG. 1 in use.

FIG. 6 shows a perspective view of a second embodiment of a design for a soccer box, from above the soccer box.

FIG. 7 shows a side view of FIG. 6.

FIG. 8 shows a top view of FIG. 6.

FIG. 9 shows a bottom view of FIG. 6; and,

FIG. 10 shows a perspective view of FIG. 6 in use.

The broken lines showing the human figure, ball and movement of the ball in FIGS. 5 and 10 and portions of the soccer box in each of the figures are for illustrative purposes only and form no part of the claim to the embodiment in which they are shown.

1 Claim, 10 Drawing Sheets---
